UNITED STATES PATENT OFFICE.

JOHN H. DERRYBERRY, OF UNIVERSITY PLACE, NEBRASKA.

COMBINED DOOR CHECK AND BUFFER.

1,053,717.

Specification of Letters Patent. Patented Feb. 18, 1913.

Application filed November 29, 1911. Serial No. 663,099.

To all whom it may concern:

Be it known that I, JOHN H. DERRYBERRY, citizen of the United States of America, residing at University Place, in the county 5 of Lancaster and State of Nebraska, have invented certain new and useful Improvements in Combined Door Checks and Buffers, of which the following is a specification.

10 The present invention relates to a combined door check and buffer, and has for its purposes to provide a device of that character which will effectively check an open door with the required resiliency as to avoid 15 jarring, and wherein an auxiliary member is employed which may or may not serve as a check to hold the door open accordingly as this is desired.

20 The invention further contemplates a device of the character in question which will be neat in appearance, easy of application to position, and one which may be manufactured at comparatively little cost to the end of making the same such that its utility 25 will readily suggest itself to many purchasers.

With these and other objects in view, the invention consists in the novel details of construction and combinations of parts more 30 fully hereinafter disclosed and particularly pointed out in the claim.

35 Referring to the accompanying drawings forming a part of this specification, in which like numerals designate like parts in all the views, Figure 1 is a top plan view of the device showing its application to a door; and Fig. 2 is a longitudinal sectional view thereof.

40 Referring to the construction in detail, the device consists in a body portion 1 constructed of sheet metal and having side portions 2 projecting at right angles therefrom. A curved and resilient metallic strip 3 has one end thereof secured to the body portion 45 1 through the medium of a rivet 4, and the opposite end portion of said strip 3 provides the door buffer, as will be apparent from an inspection of Fig. 1. The portion 3 has an aperture 5 in register with a similar 50 aperture 13 in the body portion 1, and which, with a second aperture 13 in said

body portion, receives a number of screws 14 by means of which the device as a whole is secured to the washboard B adjacent the door D.

55 The door check consists in a sheet metal member 6 and having inwardly turned side portions 7 that fit within and are hinged to the side portions 2 through the medium of a bolt or pin 8. The strip 9, also of 60 metal, is secured to the portions 6 within the side pieces 7 through the medium of a suitable pin or rivet 10, and at its end the portion 9 has an angularly disposed member 11 which terminates in a curved and resilient 65 tongue 12. The tongue 12 provides the resilient member and guide for the contacting end of a door, while the member 11, with the portion 9, provides the necessary door check, as will be apparent from an inspection 70 of Fig. 1. When the device is to be used as a combined buffer and door check, the member 9 is thrown outwardly, or in that position shown in Fig. 1, and when it is to be used as a door buffer only, the checking 75 device is adapted to be moved into that position shown in Fig. 2.

76 From the foregoing description, taken in connection with the accompanying drawings, it will be apparent that the device here 80 proposed will provide an effective combined door check and buffer, and one not liable to become easily put out of order.

It is obvious that those skilled in the art 85 may vary the details of construction and arrangement of parts, without departing from the spirit of my invention, and therefore I do not wish to be limited to such features, except as may be required by the claim.

90 Having thus described my invention, what I claim as new, is:

In a door check and buffer the combination of a body portion constructed of sheet metal and having parallel side portions; a 95 resilient metallic strip riveted to said metallic body portion between said side portions and having a curved portion projecting therefrom and providing a buffer; a sheet metal member having parallel side 100 portions disposed between the sides of said body portion; a pin passing through the side

portions of said member and body, and providing a pivot for said member; and a resilient member secured to said pivoted member between the side portions thereof; said 5 resilient member having a resilient tongue, and providing a check for holding the door against the buffer.

In testimony whereof I affix my signature in presence of two witnesses.

JOHN H. DERRYBERRY.
